UNITED STATES PATENT OFFICE.

LAVERN E. MOORE, OF PALO ALTO, CALIFORNIA.

FOLDING LADDER.

1,314,201.

Specification of Letters Patent. Patented Aug. 26, 1919.

Application filed November 20, 1915, Serial No. 62,571. Renewed January 9, 1919. Serial No. 270,438.

To all whom it may concern:

Be it known that I, LAVERN E. MOORE, a citizen of the United States, residing at Palo Alto, in the county of Santa Clara and State of California, have invented certain new and useful Improvements in Folding Ladders; and I do hereby declare the following to be a full, clear, and exact description of the invention, such as will enable others skilled in the art to which it appertains to make and use the same.

My invention relates to new and useful improvements in ladders of the collapsible or folding type and resides in the provision of a simple, inexpensive and efficient folding ladder that may be readily and easily moved into extended or folded position and when folded will take up little room.

Another object is to provide novel bracing means for the base of the ladder that will operate to securely brace the ladder when in extended position and may be folded with the ladder.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts,

Figure 1 is a side elevation of the ladder as it would appear when in extended position,

Fig. 2 is a fragmentary side elevation of the ladder as it would appear when in partly folded position,

Fig. 3 is a side elevation of the ladder as it would appear when in folded position and being partly broken away,

Fig. 4 is a view of both of the joint members for connecting the rungs to the side rails of the ladder,

Fig. 5 is a detail plan view of one of the joint members to coöperate with the members illustrated in Fig. 4,

Fig. 6 is a detail perspective view of the hinge connecting the ladder sections enlarged, and

Fig. 7 is a horizontal sectional view of the folding ladder.

Referring to the drawings by characters

of reference, the numerals 1 and 2 designate respectively the upper and lower sections of a ladder. The upper section includes side rails 3, and the lower section includes side rails 4. The side rails 3 and 4 of the respective sections are connected by rungs 5. The rungs in the upper section 1 are different from the rungs 5 in the lower section in that they are cylindrical instead of flat and connected by a different style of connecting member as will be later more fully described.

The sections 1 and 2 are hingedly connected with each other by box hinges 3^a which are formed in the nature of a rectangular receptacle with the ends open and have one side wall cut and extended at right angles for a distance equivalent to approximately half the length of the side walls and hingedly connected as at 6 with the other part of the side wall to provide a hinge leaf 7. The hinge leaf 7 is secured upon one face each of the side rails 3 of the upper section 1 and said side rails of the upper section are designed to be extended within the adjacent open ends of the body portion 80 of the hinge.

The body portions of the hinges are secured by suitable fastening elements 8 so that approximately one-half of each body portion is disposed above the lower section 85 and is thus capable of receiving the lower ends of the side rails 3 of the upper section 1.

This provides a comparatively rigid joint and obviates possibility of collapsing of the ladder when in extended position.

Hingedly secured as at 9 upon the outer faces of the side rails 4 of the lower section 2 are bracing legs 10 that extend outwardly and downwardly from said side rails 4 and are connected with each other by means of connecting bars 11 which bars are opposed to one another and arranged at the opposite faces of said legs 10. The bars 11 are rigidly secured to the lower rung of the lower section 2 and the lower ends of the side rails 4 of the said lower section 2 extends between the bars 11. The bars 11 which are arranged in parallelism are spaced apart to receive the lower portion of the ladder and the said bars 11 which are pivoted at their ends at 12 to the legs 10 are connected intermediate of their ends with the ladder at the lower end of the lower section and they are adapted to move with the lowermost rung of the ladder as clearly illustrated in Fig. 2 of 110

the drawing, the lowermost rung of the ladder being located between the bars 11.

Pivoted between the bars 11 adjacent to the outer ends thereof are U-shaped holding members or keepers 14 that are designed to receive the legs 10 and limit their movement outwardly. Pins 15 are removably inserted through the keepers 14 at points adjacent to the ends thereof and into the legs 10 so that 10 the legs are limited as to inward movement when the pins are in position. It will thus be seen that the ladder when in extended position and the legs 10 positioned as described the ladder will be prevented from 15 toppling over sidewise and a firm footing therefor provided since the legs 10 engage the ground and the side bars 4 are spaced therefrom.

The rungs 5 on the lower section 2 are connected by suitable hinges 16 with the side rails 4 and are approximately flat. Preferably the hinges consist of removable sockets to receive the ends of the rungs and a stationary hinge leaf to be secured to the 25 opposed faces of the side rails. On the left end of each of the lower rungs 5 the hinges 16 are secured upon the upper faces of said rungs and permit upward movement only, from horizontal position of said rungs. 30 The hinges are arranged in reversed form on the other ends of said rungs and it will thus be seen that locking action is provided that will prevent collapsing of the ladder when in extended position.

35 The upper rungs 5 are cylindrical and at each end carry small joint members which consist of shanks, 17 that are extended into the ends of said rungs and have annular heads 18 thereon. The socket members consist of similar members 19 and 20 each of 40 which consists of a shank 21 and an approximately semi-spherical head 22 that is formed adjacent to its periphery with an arcuate recess 23 formed by cutting away 45 a portion of said periphery. The members 19 and 20 are designed to be secured to one another after the heads 18 are placed therebetween. The shanks 17 are slideable in the recesses 23 which align with one another when the members 19 and 20 are placed 50 in position. The shanks 21 are inserted in the opposed faces of the side rails 3 of the upper section 1 and pins 24 are inserted transversely through said side rails and the shanks 21 and hold said members 19 and 20 against rotation and securely in 55 position. The recesses 23 form slots which are so arranged as to permit movement of the rungs 5 of the upper section relative to the side rails.

60 When it is desired to fold or collapse the ladder, the pins 15 are removed and the legs 10 are then free to swing in and engage the opposed faces of the side rails 3 of the lower section as shown in Fig. 2. The upper

section 1 is then folded back upon the lower section and by forcing the side rails of the sections toward one another the ladder is caused to collapse and assume an elongated collapsed form as shown in Fig. 3.

When the upper section of the ladder is folded downwardly against the lower section the hinges which connect the rungs of the upper and lower sections to the side rails of the same are arranged to fold in unison 70 but when the upper section of the ladder is swung upwardly and arranged longitudinally with respect to the lower section the hinges of the two sections are not arranged to permit the parts to fold in unison but 75 counteract each other and form a lock to prevent the latter from collapsing laterally. By this construction the ladder is automatically locked, and firmly retained in operative position and effectively prevented from 80 collapsing when arranged for use.

The rungs 5 when the ladder is folded or collapsed are interposed between the side rails and the bars 11 engage upon the side faces of the side rails and legs 10.

90 In practice, I have found that the form of my invention illustrated in the drawings and referred to in the above description, as the preferred embodiment, is the most efficient and practical; yet realizing that the 95 conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

99 What is claimed is:—

1. A folding ladder comprising spaced 105 side rails and rungs hinged to the side rails to permit the same to collapse or fold laterally, inclined braces hinged at their upper ends to the side rails at the outer face of the same and extending downwardly beyond 110 the lower end of the ladder, and horizontally disposed connecting bars arranged in parallelism and pivotally connected at their outer ends to the inclined braces intermediate of the ends thereof and connected between their 115 ends with the lower end of the ladder, said ladder being extended downwardly between the parallel connecting bars so as to be braced by the same, said connecting bars and inclined braces being arranged to fold 120 flat against the ladder when the same is folded.

2. A folding ladder comprising side rails, rungs hinged at their ends to the side rails and arranged to permit the ladder to collapse or fold laterally, inclined braces hinged at their upper ends to the outer faces of the side rails and diverging downwardly beyond the lower ends of the said side-rails, U-shaped keepers embracing and pivotally 130

mounted on the inclined braces at points intermediate of the ends thereof, parallel transverse connecting bars receiving the lower end of the ladder and connected with the same, said parallel bars being pivoted at their ends to the said keepers, and foldable with the inclined braces flat against the ladder when the ladder is collapsed, and

5 pins piercing the said keepers and adapted to hold the braces against inward movement. 10

In testimony whereof I affix my signature in presence of two witnesses.
